CLAIM

The ornamental design for an "assembled chair", as shown
and described.

DESCRIPTION

FIG. 1 is a front elevational view of the said "assembled
chair" illustrating my new design;

FIG. 2 is a right side elevational view of the said "assembled
chair" the opposite side being a mirror image thereof;

FIG. 3 is a rear elevational view thereof;

FIG. 4 is a bottom plan view thereof;

FIG. 5 is a top plan view thereof;

FIG. 6 is a perspective view of the said "assembled chair";
and,

FIG. 7 is a perspective view of an alternative embodiment of
the present invention wherein the sole difference is the
attached stool. The opposite side is a mirror image of that
shown.
